(57) **CLAIM**

The ornamental design for a vehicle tail lamp, as shown and
described.

DESCRIPTION

FIG. 1 is a perspective view of a vehicle tail lamp in
accordance with an embodiment of the present invention;
FIG. 2 is a front view of the tail lamp of FIG. 1;
FIG. 3 is a side view of the tail lamp of FIG. 1;
FIG. 4 is a top view of the tail lamp of FIG. 1;
FIG. 5 is a bottom plan view of the tail lamp of FIG. 1; and,
FIG. 6 is a perspective view of a tail lamp in accordance with
another embodiment of the present invention.
The tail lamp of FIGS. 1-5 is intended for the right rear
fender of a vehicle. FIG. 6 shows an alternate embodiment
for the same tail lamp intended for use on the left rear fender
of the vehicle. Other than the location and orientation, the
tail lamp for either rear fender of the vehicle are the same.
The tail lamp of the present invention may be constructed as
a unitary piece or may comprise a multi-piece product
wherein each portion thereof is the same or a different color.
